UNITED STATES PATENT OFFICE

NELSON S. WELK, OF ATHENS, OHIO, ASSIGNOR TO THE MCBEE BINDER COMPANY, OF ATHENS, OHIO, A CORPORATION OF OHIO

COMPRESSING MEANS FOR FILING TRAYS

Application filed September 19, 1925. Serial No. 57,299.

My invention relates to filing trays, and particularly to releasable, compressible, means for firmly holding the filed papers in position.

5 My object is to provide novel and expedient means for this purpose, in which the forward presser plate and the follower plate may each be easily and quickly released from their compressing positions so as to provide 10 ready and convenient access to any of the filed papers.

My invention consists of certain details of construction hereinafter set forth, pointed out in my claims, and illustrated in the accompanying drawings, in which

15 Fig. 1 is an exploded perspective view of the filing tray and cover, a part of the cover being broken away to illustrate the hinging and locking means;

20 Fig. 2 is a detailed view of the wedge-shaped lever which controls the positioning of the presser plate;

Fig. 3 shows a rear elevation view of the follower plate and the means by which it 25 is locked in, and released from, pressure;

Fig. 4 shows a longitudinal sectional view of the tray clearly illustrating the means for controlling the positioning of both the forward presser plate and the follower plate, the dotted lines indicating the released positions of these plates;

Fig. 5 shows a perspective view of the tray, illustrating the controlling means for the follower plate.

35 Referring to the accompanying drawings, reference numeral 10 is used to indicate a filing tray formed with the usual side walls, end walls and base, and the numeral 11 indicates the cover therefor. The rear end wall 40 is formed, at its top, with one element 12 of a pivotal connection, the companion element 13 of this pivotal connection being fixed to the cover 11. By mating these elements a pivotal connection is formed which seats the 45 rear wall of the cover to the rear wall of the tray, and when the forward end wall of the cover is locked to the forward end wall of the tray (diagrammatic means for which 50 is illustrated at 14) the elements 12 and 13

are locked in position so that the cover 11 is firmly locked to the filing tray.

The follower plate 21 is hinged to a base 15 mounted, in the customary way, for slide- 55 able movement along the base of the tray, and this movement is controlled by the spring-actuated lever 16. The manner in

which the base 15 is movable is not specifically described, as it will comprise the basis for a separate application, and it is only suffi- 60

cient for the purposes of this application that the base be mounted for slideable and controlled movement. The numerals 17 and 18 indicate companion angular levers, each being pivotally mounted at 19 to the common support 20. These levers are exactly the 65 same in every respect, both as to shape and position, and are simultaneously operated and controlled. Their mounting and con-

struction is such that when the levers are at their downward position, as shown in the full lines in Fig. 4, their forward ends force the follower plate 21 to a substantially vertical position, and contact the same, thereby holding it in this substantially vertical position. Secured to the follower plate 21, and 70 mounted for pivotal movement therefrom as shown at 22, is a control rod formed with two arms, 23 and 24 respectively, which project toward the angle levers, 17 and 18 re- 75

Fig. 4 shows a longitudinal sectional view of the tray clearly illustrating the means for controlling the positioning of both the forward presser plate and the follower plate, the dotted lines indicating the released positions of these plates;

Fig. 5 shows a perspective view of the tray, illustrating the controlling means for the follower plate.

35 Referring to the accompanying drawings, reference numeral 10 is used to indicate a filing tray formed with the usual side walls, end walls and base, and the numeral 11 indicates the cover therefor. The rear end wall 40 is formed, at its top, with one element 12 of a pivotal connection, the companion element 13 of this pivotal connection being fixed to the cover 11. By mating these elements a pivotal connection is formed which seats the 45 rear wall of the cover to the rear wall of the tray, and when the forward end wall of the cover is locked to the forward end wall of the tray (diagrammatic means for which 50 is illustrated at 14) the elements 12 and 13

the tray by the positioning of the sliding plate 15.

The numeral 27 indicates a forward presser plate which is hinged to a support 28 mounted in the forward part of the tray, the hinge being at the base of the plate, as shown clearly in Fig. 4. This support 28 preferably comprises a wall, spaced from the forward wall of the tray, and through this support wall 5 I have provided an orifice 29. A control lever 30 is mounted, for pivotal movement, parallel to the plate 27, and on the forward end of the control lever is a wedge-shaped element 31 which is positioned at right angles 10 to the plate 27. Also secured to the plate 27 is a lug 32 which projects forwardly through the orifice 29, and has a hook 33 formed thereon to contact the front side of the wall of the support 28, so as to negative the possibility of the plate 27 moving too far rearwardly on its hinge, when papers are not in 15 the cabinet. The numeral 34 indicates a handle on the control lever 30 for operating the same, and the numeral 35 indicates a stop 20 member on the plate 27 to determine the upward and downward limits of movement of 25 the lever 30.

The construction and positioning of the plate 27 and lever 30 are such that when the 30 lever is moved so as to lift the wedge-shaped end 31, the plate 27 may be inclined forwardly, as shown by the dotted lines in Fig. 4, so as to provide ready and convenient access to papers that are filed, or to release 35 the pressure so papers may be inserted. When the lever 30 is moved so as to force the wedge end 31 downwardly, the wedge is inserted between the support plate 28 and the plate 27, thereby forcing the plate 27 forwardly into a substantially vertical position 40 pressing against the papers in the tray.

From my construction the presser plate 27 and the follower plate 21, when they are both moved and locked in their vertical positions, 45 will hold the papers firmly in position—it, of course, being obvious that the follower plate has been moved forwardly to proper position by the positioning of the plate 15. When it is desired to release the pressure of 50 the plates on the papers, the position of the plate 15 is not changed, but the operator simply lifts the ends 25 and 26 of the control lever, thus elevating the pivotal joint between the angle levers and the control lever, which 55 elevates the angle levers and permits the plate 21 to be moved into its rear position, as shown by the dotted lines in Fig. 4. The control lever 30 is also moved upwardly so as to withdraw the wedge end 31, thereby permitting 60 the presser plate 27 to be moved forwardly, and these two plates being released simultaneously furnish most ready access to the papers filed, or makes it very easy to file any papers desired.

Having thus described my invention, what

I claim and desire to secure by Letters Patent of the United States, is:

1. In a filing tray, a presser means comprising a support affixed in the forward end of the tray; a plate hinged to said support, 70 a lever having a wedge-shaped end, pivoted to said plate, so arranged that the wedge end may be forced downwardly between the plate and a wall of the support for forcing and retaining the plate in a substantially vertical 75 position, and may be moved upwardly to withdraw the wedge end from contact with the companion wall, and thereby permit the plate to be inclined forwardly from its hinge.

2. In a filing tray, a presser means comprising a support affixed in the forward end of the tray and having a wall spaced from the front of the tray; a plate hinged to said support, a lever, provided with a right-angular positioned wedge arm, pivotally mounted upon the said plate; a control arm secured to the said plate and projecting forwardly through a slot in the support wall, said arm being provided with a hook to contact the front side of the wall of the support and 80 limit the movement of the plate, substantially 85 as shown and described.

3. In a filing tray, a presser means comprising a support affixed in the forward end of the tray; a plate hinged to said support; 90 a wedge-shaped member secured to the plate; control means whereby the wedge-shaped member may be forced between the plate and the support to force the plate to a substantially vertical position, or withdrawn 95 from between the plate and the support to permit the plate to be inclined forwardly, substantially as shown and described.

4. In a filing tray, a follower comprising a plate secured for slidable movement in the base of the tray; means to lock the plate in any desired position; a presser plate hinged to the slidable plate; angle levers pivotally secured to the slidable plate and projecting forwardly to the hinged plate; a control rod 105 pivotally secured to the hinged plate and having pivotal connection with the angle levers, the construction being such that when the angle levers are moved downwardly upon their pivots they will move the hinged plate 110 to a substantially vertical position and hold it there, and at the same time positioning the pivotal connection of the control rod below a dead center, substantially as shown and described.

5. In a filing tray, a follower comprising a plate secured, for slidable movement, in the base of the tray; means to lock the plate in any desired position; a follower plate hinged to the slidable plate; angle levers pivotally secured to the slidable plate; a control rod pivotally secured to the follower plate and also pivotally secured to the angle levers, the construction being such that when the angle levers are in their downward position the con- 115 120 125 130

nection of the angle levers with the control rod will be depressed below a line extending between the connection of the control rod with the follower plate and the connection of the angle levers to the slidable plate, substantially as shown and described.
